(57) **CLAIM**

The ornamental design for a bottle carrier, as shown and described.

DESCRIPTION

FIG. 1 is a left side view of a bottle carrier, showing my new design; the right side view being a mirror image;

FIG. 2 is a front view thereof;

FIG. 3 is a top view thereof;

FIG. 4 is a rear view thereof; and,

FIG. 5 is a bottom view thereof.

The broken line disclosure of a bottle in FIGS. 1, 2 and 4 is for illustrative purposes only and forms no part of my design.

1 Claim, 2 Drawing Sheets

FIG. 1

FIG. 3

FIG. 4

FIG. 2

FIG. 5
